UNITED STATES PATENT OFFICE.

HARRISON L. STALEY, OF MARTINSVILLE, INDIANA.

MOTION-AUGMENTING PENDULUM-GEARING.

1,108,938.

Specification of Letters Patent.

Patented Sept. 1, 1914.

Application filed April 24, 1911. Serial No. 622,927.

To all whom it may concern:

Be it known that I, HARRISON L. STALEY, a citizen of the United States, residing at Martinsville, in the county of Morgan and State of Indiana, have invented a new and useful Motion-Augmenting Pendulum-Gearing, of which the following is a specification, reference being had to the accompanying drawings, and to the letters and figures of reference marked thereon.

10 This invention relates to pendulum gearing that is designed for producing motion, more especially for the operation of rubbing devices of washing machines, particularly such devices as require rotary-reciprocating motion, the invention having reference more particularly to means for augmenting the motion of pendulum gearing.

15 The primary object of the invention is to provide improvements in motion augmenting gearing, especially of the pendulum type, to the end that such gearing shall be adapted to be operated with the minimum degree of manual effort; a particular object being to provide lever types of gearing with motion augmenting means that shall be so constructed and arranged as to be adapted to be energized for imparting energy, and to absorb or obviate the shocks incidental to the reversing of the direction of motion of the levers in operation; a still further object being to provide pendulum washing machine gearing with motion augmenting means so constructed that such means shall 20 constitute a steady weight for the pendulum, and so that such gearing shall in a large measure be "live weight", or movable bodily while its parts are active for the transmission of energy.

25 40 Other objects of the invention of minor importance will appear in the following description of the invention.

The invention consists essentially in a bodily movable rotary gearing for storing 45 energy imparted thereto and giving off the energy for the actuation of other gearing; the invention consisting more specifically in providing a pendulum or a lever with a weight comprising rotary gearing, more especially with speed increasing gearing; and the invention consists further in the novel parts and in the combinations and arrangements of parts as hereinafter particularly described and claimed.

50 55 Referring to the drawings, Figure 1 is a perspective view of the invention as pref-

erably constructed and applied to a washing machine; Fig. 2 a vertical central sectional view; Fig. 3 a fragmentary horizontal section approximately at the plane of the line A A in Fig. 1; Fig. 4 a fragmentary inverted plan view; Fig. 5 a fragmentary sectional view on the line B B in Fig. 2; Fig. 6 a perspective view of a part of a supporting bearing for the shaft of the rubbing device; Fig. 7 an inverted perspective view of another part of the shaft bearing; Fig. 8 a perspective view of a connecting rod comprising a part of the improved gearing; and, Fig. 9 a fragmentary section on the line C C in Fig. 2.

Throughout the different figures of the drawings similar reference characters indicate corresponding elements or features of construction herein referred to and described.

As illustrating one of the purposes for which the invention is adapted to be used, a washing machine is shown in connection with the invention, the machine including a tub comprising a side wall 1, a bottom 2, supporting legs 3, a cover section 4 secured on top of the side wall, and a movable cover section 5 connected to the section 4 by means of hinges 6. A suitable gear support 7 is placed upon the section 5 of the cover and has a journal box 8 thereon which extends through the cover section, the support having also an upright guide 9 thereon. A cap 10 is placed upon the support 7 and with it is secured to the cover section 5, the cap being provided with a journal box 11. A rubber actuating shaft 12 is rotatably mounted in the journal boxes 8 and 11 and extends into the tub, and it is movable vertically in the journal boxes, the lower end of the shaft having a flange 13 thereon to which a rubbing plate 14 is secured, the latter being provided with a suitable number of pins 15 whereby to move the articles to and fro in the tub. A pinion 16 is arranged between the support 7 and the cap 10, and the shaft is movable vertically in the pinion, the pinion being provided with a spline 17 enabling it to impart rotary-reciprocating motion to the shaft. The aforementioned construction may be variously modified as may be desired.

As preferably constructed a pivot block 18 is secured to the exterior of the wall 1 of the tub and it is provided with a pivot pin 19 to which a lever 20 is connected, the

lever preferably being provided with a jaw 21 receiving the pivot pin. The lever is provided with pivoting ears 22 to which one end of a rack bar 23 is connected by means 5 of a pivot pin 24, the rack bar extending upon the support 7 against the guide 9 and having gear teeth 25 on one side thereof in engagement with the pinion 16 so as to impart motion to the pinion. The upper side 10 of the cover section 5 is provided with a guide plate 26 against which the free end of the rack-bar slides when the cover section is moved upward and backward on its hinges, so as to lift the rack bar from engagement 15 with the pinion. The lever preferably has a separate wooden handle portion 27 of suitable length to afford ample leverage, and preferably it is provided with laterally extending handles 28 and 28'. 20 The pendulum or motion-augmenting medium for assisting in the operation of the lever and gearing connected therewith and for steadyng the motion thereof, and for continuing the movement after being set 25 in motion, preferably comprises an arm 20' formed integrally or otherwise connected with the lever 20 so as to preferably be suspended from the pivot pin 19, a portion of the arm being so formed as to constitute 30 an offset crank box 29 which is open at the side toward the legs of the tub, the crank box being below the plane of the bottom of the tub, and it has a journal box 30 thereon extending downwardly so 35 as to constitute the lower end portion of the arm which is provided at its lower end with an extension 31 projecting laterally in a plane between two of the legs of the tub, the lower end portion having also a relatively 40 shorter portion 31' extending from the extension 31 around the end portion of the journal box. A crank shaft 32 is mounted uprightly in the journal box 30 and extends therethrough, the upper end of the 45 shaft having a crank arm 33 thereon provided with a ball shaped crank pin 34, and a suitable wheel 35 is secured to the shaft at the lower end of the journal box 30, the wheel preferably being a toothed wheel, as 50 illustrated. A connecting rod 36 is provided which has a concave socket part 37 formed integrally upon one end thereof, and a companion socket part 37' secured detachably to the rod, said socket parts together embracing the ball shaped crank pin 34. The opposite end portion of the rod 36 has a pivot hole 38 therein to receive a horizontally arranged pin 39 which is connected to a pivot block 40. A pivot head 41 55 is secured to the under side of the bottom 2 of the tub and provided with a vertical pivot pin 42 whereby the pivot block 40 is connected to the pivot head. It will be clear from the foregoing that when the lever 20 is rocked on its supporting pivot the

shaft 32 is moved axially toward or from the pivot head 41, but the crank pin 34 is held against movement in that direction, and consequently the shaft is caused to rotate and carry the crank pin transversely 70 in an arc about the pivot pin 42, the pivot pin 39 permitting the rod 36 to adjust itself vertically during the swinging movement of the arm in an arc about the pivot pin 19. The arrangement is such that the weight of 75 the metal carried by the lower end of the arm serves as a plumb to hold the lever and pendulum arm in mid position when at rest, and so that the crank arm 33 extends transversely or at "quarter" position in order that when the lever again is moved, the crank arm not being on dead center must cause rotation of the shaft 32. The wheel 35 may be of such size and weight as to serve as a balance-wheel, but 80 preferably a stub shaft 43 is mounted on the extension 31, and a pinion 44 and a relatively large balance-wheel 45 is mounted on the stub shaft, the pinion being in mesh with the toothed wheel 35 and suitably connected to the balance-wheel, the pinion and balance wheel preferably being formed integrally and mounted rotatably on the stub shaft, so that the balance wheel must rotate 90 at relatively high speed when the wheel 95 35 is rotated.

A suitable gear case is provided which preferably comprises an appertured plate 46 extending about the extensions on the lower end of the pendulum and suitably secured thereto, the plate having a flange 47 thereon extending downwardly about the gear wheel 35 and the pinion 44. The pendulum is provided with push bars 48 and 48' which preferably are cast on or otherwise fixedly connected to the plate 46 of the gear case, to enable the operator to use his feet when in sitting position to assist in operating the pendulum gearing, by placing the feet upon the push bars. 110

It should be understood that the pendulum and the gearing may be variously modified in detail and may be adapted to be used in connection with various types of other gearing. It is obvious also that the 115 balance wheel may be variously arranged on the pendulum arm as may be most convenient, in order to obtain gyroscopic effect in steadyng the motion of the operating lever, especially during the periods when 120 the direction of movement of the lever is reversed.

In practical use the handle portion 27 of the lever is moved so that the rack bar 23 is given reciprocating movement for operating the shaft 12, the lever at the same time causing the pendulum arm to swing to and fro so as to cause rotation of the shaft 32 which in turn drives the wheels connected therewith while the wheels are 125 130

moved bodily with the pendulum and serve as weighting material, while at the same time acting to continue the motion, not only over the dead centers of the crank, but for 5 a time after having been manually put in motion, the gearing therefore enabling the operating lever to be easily kept in motion.

Having thus described the invention, what is claimed as new is—

10 1. Gearing including an arm having an offset crank box and also a journal box, a shaft rotatable in the journal box and having a crank arm movable in the crank box, and a wheel larger than the crank arm fixed 15 on the shaft for receiving and imparting energy to rotate the shaft.

20 2. Gearing including a pendulum device swingingly suspended and having on its free end a relatively movable weight element, and means acting on movement of the device for moving the weight element to store energy therein and enabling the weight element when energized to impart swing- 25 ing motion to the device.

30 3. Gearing including a pendulum device swingingly suspended, a pivoted lever for swinging the device, a wheel rotatably mounted on the device, and means acting on movement of the device for rotating the wheel to store energy therein and enabling the wheel when energized to impart swing- 35 ing motion to the device for transmitting motion to the lever.

40 4. Gearing including a support, an arm swingingly suspended on the support, a shaft rotatably mounted on the arm and a wheel thereon, and means connected with the shaft acting, on swinging movement of the arm, to automatically rotate the shaft and continue rotating the shaft during the reversing interruptions in the swinging movement of the arm.

45 5. Gearing including a support, an arm swingingly suspended on the support, a balance-wheel rotatably mounted on the arm, means for rotating the balance-wheel to store energy therein, and means enabling the balance-wheel when energized to impart swinging motion to the arm.

50 6. Pendulum gearing including a support, a lever pivoted to the support and having a pendulum arm thereon, a wheel rotatable on the arm, continuously rotatable means mounted on the arm and operatively connected with the wheel, and means connected with the rotatable means and the support for rotating said means and enabling the wheel to rotate and continue rotation of the continuously rotatable means.

60 7. Gearing including a support, an arm swingingly suspended on the support, a shaft rotatably mounted on the arm, a balance-wheel rotatably mounted on the arm, means connected with the shaft acting, on swinging movement of the arm, to rotate

the shaft, and bodily movable speed-increasing gearing connecting the balance-wheel with the shaft for rotating the balance-wheel faster than the shaft.

8. Pendulum gearing including a support, 70 a lever pivoted to the support and having a pendulum arm thereon, a shaft and also a balance-wheel rotatably mounted on the arm, means operatively connected with the shaft and the support for rotating the shaft, 75 a gear wheel secured to the shaft, and a pinion fixed on the balance-wheel and in engagement with the gear wheel.

9. Pendulum gearing including a support, 80 an arm swingingly suspended on the support, a balance-wheel rotatably mounted on the arm, a lever mounted pivotally on the support and operatively connected with the arm, a rotary-reciprocatory shaft mounted on the support and operatively connected with the lever, and means connected with the arm and the balance-wheel and also with the support for rotating the balance-wheel. 85

10. Motion-augmenting pendulum gearing including an arm swingingly suspended and 90 having on its free end a relatively movable weight element, a rotary-reciprocatory shaft, a pivoted lever for imparting swinging movement to the arm and operatively connected with the shaft for operation thereof, 95 and means enabling the swinging arm to automatically move the weight element and also enabling the weight element when set in motion to continue the swinging movement of the arm, for transmitting stored energy from the weight element to the shaft. 100

11. In washing machine gearing, the combination with a stationary support, of a lever pivotally connected to the support and having a pendulum arm thereon, a pivot head secured to the support, a shaft rotatably mounted on the arm and having a crank-arm thereon, a wheel secured to the shaft, and a connecting-rod connected to the crank arm and also to the pivot head. 105 110

12. In washing machine gearing, the combination with a stationary support, of a lever pivotally connected to the support and having an arm thereon, the arm having a crank-box and also a journal-box thereon, a shaft rotatably mounted in the journal-box, a crank arm on the shaft and movable in the crank-box, a wheel secured to the shaft, a pivot-head secured to the support, and a connecting-rod connected to the crank-arm and also 115 to the pivot-head. 120

13. In washing machine gearing, the combination with a support, of a lever pivotally connected to the support and having an arm thereon, a shaft rotatably mounted on 125 the arm, a wheel secured to the shaft, a crank-arm secured to the shaft and having a ball-shaped crank-pin thereon, a pivot-head secured to the support and having a pivot thereon, a pivot-block connected to the 130

pivot, and a connecting-rod having a socket on one end embracing the crank-pin, the opposite end of the connecting-rod being pivotally connected to the pivot-block.

14. In washing machine gearing, the combination with a stationary support, of a lever pivotally connected to the support and having a pendulum arm thereon, a pivot-head secured to the support, a shaft rotatably mounted on the arm and having a crank-arm thereon, a balance-wheel rotatably mounted on the arm, a connecting-rod connected to the crank-arm and also to the pivot-head, and speed-increasing gearing between the shaft and the balance-wheel carried by the arm for rotating said balance-wheel faster than said shaft while moving bodily with said arm.

15. In washing machine gearing, the combination with a support, a top hinged on the support, a pivot-block secured to the upright side of the support, a pivot-head secured to the under side of the bottom of the support, a shaft mounted in the top of the support to move rotatively, a pinion connected with the shaft, and a rack-bar normally in engagement with the pinion, of a lever pivotally connected to the pivot-block and also to the rack-bar and having an arm thereon provided with a journal-box, a crank-shaft rotatably mounted in the journal-box, a crank-arm on the shaft provided with a crank-pin, a connecting-rod connected at one end with the pivot-head to move angularly horizontally and also vertically and having its opposite end connected to the crank-pin, a guide-plate secured upon the said top for guiding the rack-bar from said pinion on movement of said top on its hinge, a gear wheel secured to the crank-shaft, a balance-wheel rotatably mounted on the arm and a pinion thereon in engagement with the gear wheel, and a gear case secured to the arm and extending over the gear wheel and the pinion of the balance-wheel, said gear case having push-bars thereon.

16. In washing machine gearing, the combination of a stationary support, a prime actuator movably mounted on the support, a shaft rotatably mounted on the support, and means operatively connecting the shaft with the prime actuator, with a swingingly supported pendulum arm operatively connected with the actuator to swing on movement of the actuator, motion augmenting means mounted on the arm and movable relatively to the arm, and means coöperating with the support and the arm acting, on movement of the arm, to automatically move the augmenting means, for storing and giving off energy primarily generated by the prime actuator.

17. In washing machine gearing, the combination with a stationary support, a shaft rotatably mounted on the support, a prime

actuator movably mounted on the support, and means operatively connecting the prime actuator with the shaft, of a pendulum operatively connected with the actuator and supported to swing on movement of the actuator, the pendulum being provided with a combined live-weight element and motion augmenting means including a device movably mounted on the pendulum, and means enabling the pendulum on swinging movement to move the device relatively to the pendulum and enabling the device, when set in motion, to continue in motion during reversing interruptions of swinging motion of the pendulum, for starting the pendulum after interruptions of movement and augmenting the power of the prime actuator to operate the shaft.

18. In gearing, the combination with a swingingly supported device, of a balance-wheel rotatably mounted on the device, a movably supported prime actuator operatively connected with the device, and movable means actuated on movement of the actuator and the device and rotating the balance-wheel at relatively high speed, for storing energy generated by the actuator to be subsequently imparted to the actuator.

19. In washing machine gearing, the combination with a supporting structure, a pendulum swingingly supported by the structure, and a movable prime actuator operatively connected with the pendulum and on movement imparting motion thereto, of a balance-wheel rotatably mounted on the pendulum, operable gearing operatively connected with the balance-wheel and having a crank arm, the gearing being carried by the pendulum, and means coöperating with the structure and the crank arm for operating the gearing and rotating the balance-wheel on movement of the pendulum.

20. In washing machine gearing, the combination with a supporting structure, a movable prime actuator, and a pendulum device pivotally supported to swing under the structure and operatively connected with the actuator, of a balance-wheel rotatably mounted on the device, operable gearing for rotating the balance-wheel carried by the pendulum device, and means coöperating with the structure and the gearing to operate the gearing and rotate the balance-wheel on movement of the pendulum device.

21. In washing machine gearing, the combination with a supporting structure, a pendulum device swingingly supported by the structure, and a movable actuator for swinging the pendulum device, of a balance-wheel and also actuating gearing therefor movably mounted on the pendulum device, the gearing being provided with means coöperating with the structure for moving the gearing on movement of the pendulum device.

22. In washing machine gearing, the com-

bination with a supporting structure, of a pendulum device swingingly supported by the structure, a wheel rotatably mounted on the pendulum device and provided with a 5 crank arm for rotating the wheel, and means coöperating with the structure and the crank arm for rotating the wheel on movement of the pendulum device.

23. In washing machine gearing, the combination with a supporting structure, reciprocatory gearing mounted upon the top of the structure, and an actuating lever pivotally supported on one side of the structure and operatively connected with the gearing, 10 of motion augmenting pendulum gearing including swinging and also rotatable means movably supported and actuated by the lever to swing under the structure, and means co-

operating with the supporting structure and the gearing for rotating the rotatable means 20 on swinging movement of the swinging means.

24. In washing machine gearing, a swingingly supported pendulum device provided on its free end portion with relatively high-speed rotary motion augmenting and weighting appliances having means connected therewith for rotating the appliances on swinging movement of the pendulum device.

In testimony whereof, I affix my signature 30 in presence of two witnesses.
